By *O. B. Anthony, Jr., Attorney.*

UNITED STATES PATENT OFFICE.

JOSEPH P. NAMI, OF CRISTOBAL, CANAL ZONE, PANAMA.

STIRRUP.

1,378,713.

Specification of Letters Patent. Patented May 17, 1921.

Application filed April 12, 1919. Serial No. 289,498.

To all whom it may concern:

Be it known that I, JOSEPH P. NAMI, a citizen of the United States, residing at Cristobal, in the Canal Zone, Panama, have 5 invented certain new and useful Improvements in Stirrups; and I do hereby declare the following to be a full, clear, and exact description of the invention, such as will enable others skilled in the art to which it 10 appertains to make and use the same.

This invention relates to stirrups for aeroplanes, and other air crafts, and the primary object of the invention is to provide improved means for facilitating the mounting 15 of an aeroplane, said means being flush with the sides of the fuselage, so as to reduce wind resistance and to prevent the same from being readily located by unauthorized persons desiring to mount the aeroplane.

Another object of the invention is to provide an improved stirrup to facilitate the mounting and climbing into the fuselage of 20 an aeroplane, which is formed in the fuselage, so as not to present a resisting surface to the wind.

A further object of the invention is to provide an improved stirrup for aeroplanes having a cover plate constructed to conform 25 to the contour of the fuselage, and which is arranged to normally extend flush with the sides thereof, so as to present a smooth unbroken surface, so as to prevent head resistance, wind eddying, etc., as is usual in 30 the ordinary types of stirrups now in vogue.

A still further object of the invention is to provide an improved stirrup for aeroplanes of the above character, which is durable and efficient in use, one that is simple 35 and easy to manufacture, and one that can be placed upon the market at a reasonable cost.

With these and other objects in view, the invention consists in the novel construction, 40 arrangement and formation of parts, as will be hereinafter more specifically described, claimed and illustrated in the accompanying drawings, forming a part thereof in which:

Figure 1 is a fragmentary side elevation 45 of an aeroplane fuselage, showing the improved stirrup applied thereto.

Fig. 2 is a detail cross section taken on the line 2—2 of Fig. 1.

Fig. 3 is a similar view, showing the 50 cover plate or flap swung open.

Fig. 4 is a detail section taken on the line 4—4 of Fig. 2.

Fig. 5 is a detail vertical sectional view illustrating a modified form of the invention.

Referring to the drawings in detail, wherein similar reference characters designate corresponding parts throughout the several views, the numeral 1 indicates a fuselage or body of an aeroplane or other 55 air craft and the same includes the outer skin 2 and the longitudinally extending braces or longérons 3. The improved stirrup 4 includes a substantially flat plate 5 having the upper surface thereof corrugated, as at 6, so as to prevent the aviator's foot from slipping thereon, when climbing or mounting into the fuselage, and the same is secured by fastening elements 7 or other suitable means to one of the longérons 3. 70 The skin 2 is provided with an arch shaped or any other preferred form of opening 8, in direct alinement with the plate 5 and large enough for the toes of the foot of the aviator to be placed therein. The plate 5 80 may be positioned at a suitable point and secured to any support on the fuselage so as to permit of the convenient mounting of an aviator in the fuselage. A flap 9 is provided for normally closing the opening 8 in the 85 fuselage, and the same is adapted to lie flush with the outer surface thereof, so as to present a smooth unbroken surface and thus eliminate any head resistance, wind eddying and the like. The flap is normally 90 held in its vertical closed position by means of spring hinges 10, which are secured to the upper inner surface of the flap.

Thus it will be seen that when it is desired to mount the fuselage, the foot of the 95 aviator is placed in the opening and upon the plate 5, which forms a sufficient foot hold for permitting the easy mounting of the plane. Upon withdrawal of the foot, the flap is swung to its closed position by 100 means of the spring hinges and thus an unbroken surface of the fuselage is again presented. The flap in its closing movement will sweep off any debris from the plate 5 that might have been deposited by 105 the aviator's foot in mounting the aeroplane.

It is to be understood that any suitable type of hinges and springs may be employed for closing and hinging the flap and the 110

same, if so desired, may be hinged on the side or bottom edges thereof. When hinged at the bottom edge of the opening, the same forms a rest for the foot when the flap is 5 swung inwardly.

The stirrup may be constructed of wood, metal or the like, and as many stirrups as required may be fitted into any fuselage, pontoon, motor nacelle or the like of an 10 air craft, and the same can be constructed in the form of a permanent streamline ladder, as a means of climbing into airships, gondolas, aerobuses or any type of aerial vehicles.

15 The stirrup being almost invisible may be marked with paint, luminous material, or the like, so as to be easily located by day or by night.

A light metal partition of any desired 20 form may be mounted at the rear of the stirrup plate 5, so as to divide the stirrup off from the interior of the fuselage or other body to prevent dirt or other debris from entering into the fuselage or other 25 body through the stirrup opening.

By eliminating the resistance caused by the ordinary types of stirrups now in vogue, an aeroplane fitted with my improved stirrup will be able to acquire a greater rate 30 of speed, than the ordinary aeroplane.

In practice, I have found that the form of my invention illustrated in the accompanying drawings and referred to in the above description, as the preferred embodiment, is

the most efficient and practical; yet realizing the conditions concurrent with the adoption of my device will necessarily vary, I desire to emphasize that various minor changes in details of construction, proportion and arrangement of parts may be resorted to, when required without sacrificing any of the advantages of my invention as set forth.

What I claim as new is:

In combination, a fuselage having an 45 opening and a brace secured to its inner face and located in a plane below the opening, a substantially flat horizontally disposed plate secured to the top face of the brace and disposed in a plane with the lower wall 50 of said opening and having a serrated upper face, said plate extending from the inner face of the fuselage to a point beyond the brace to form a step of a length substantially equal to the length of a person's foot, 55 and a flap hinged to the inner face of the fuselage at the upper end of the opening and adapted to normally close said opening by gravity and having its outer face flush with the outer face of the fuselage and capable 60 of swinging inwardly by pressure of a person's foot thereagainst to expose the plate.

In testimony whereof I affix my signature in presence of two witnesses.

JOSEPH P. NAMI.
